UNITED STATES PATENT OFFICE.

CHARLIE E. LOCKE, OF LOUISVILLE, KENTUCKY.

AUTOMATIC MAIL-BAG CATCHING AND DELIVERING APPARATUS.

SPECIFICATION forming part of Letters Patent No. 672,832, dated April 23, 1901.

Application filed August 24, 1900. Serial No. 27,949. (No model.)

To all whom it may concern:

Be it known that I, CHARLIE E. LOCKE, a citizen of the United States, residing at Louisville, in the county of Jefferson and State of Kentucky, have made certain new and useful Improvements in Automatic Mail - Bag Catching and Delivering Apparatus, of which the following is a specification.

My invention is an improvement in that class of apparatus which includes an automatic mail-bag catcher arranged on a postal car and another catcher arranged and suspended outside of the track.

The invention includes reliable means for suspending and automatically releasing and catching mail-bags on cars and at stations.

In the accompanying drawings, Figure 1 shows my invention as arranged for operation at a station, the car being shown in vertical section. Fig. 1^a is a sectional view illustrating a catch for holding a swinging mail-bag frame in normal position. Fig. 2 is a plan view of the apparatus, the car being shown in section. Fig. 3 is a side view of the spring stop and holder for the swinging frame applied to the car, the view taken being a section on the line 3 3 of Fig. 2. Fig. 4 is a side view of the safety - catch for the swinging frame arranged at a station, the view being taken as a section on the line 4 4 of Fig. 2. Fig. 5 is a perspective view illustrating the arrangement of the torsion-lever for opening the safety - catch for releasing a swinging frame on a car. Fig. 6 is a longitudinal section of the spring-stop for the swinging frame arranged at the station. Fig. 7 is a plan view of the same, part being in section. Fig. 8 is a perspective view of a portion of the device shown in Figs. 6 and 7. Fig. 9 is an end view 40 of one of the mail-bag catchers. Fig. 10 is a perspective view of a modification of the catcher. Fig. 11 is a plan view of the mail-bag suspending and releasing device; and Fig. 12 is a perspective view of such device, including a portion of the torsion-lever suspended from and connected to it.

Referring in the first instance to Figs. 1 and 2, A and B indicate mail-bag catchers, one, A, being connected with a car C and the other, B, being located at a station. The catcher A is suspended elastically by coil-springs *a* from a horizontal rod or bar *d*, forming part

of a swinging frame D, which is journaled in suitable bearings *d'*, attached to the jamb of the car-door. The said springs *a* are connected with a sleeve *d²*, which fits loosely on the rod *d* and is held thereon by screw-clamps *d³*, so that it is adapted for convenient attachment and removal. The other catcher, B, is similarly attached to the horizontal rod *e* of a swinging frame E by means coil-springs *e'*, secured to the sleeve *e²*, which is held in place by a clamp *e³*. The said frame E is pivoted to swing in a horizontal plane by means of the rod *e⁴*, which is pivoted in a post F, supported upon ties G, (see Fig. 2,) which are extended laterally from the track for that purpose. This supporting-post F is arranged at the station or other place where mail is to be taken and delivered. The swinging frame E is held projected toward the track by means of a swinging spring-catch H, (see Figs. 1 and 1^a,) which is pivoted on the upper end of an arm *f*, projecting laterally and upward from the post F. The catch H is adapted to rock on its pivot, but is held normally vertical by means of springs *h*, which are coiled around its pivot and extend up on its sides. The upper end of the catch is recessed to receive the rod or bar *e*, forming part of the swinging frame E. The tension of the spring *h* holds the catch normally vertical, whereby the frame E is held against the pressure of the wind or from being accidentally swung out of position; but the catch yields and allows the frame to swing when the mail-bag is received by the catcher A. I show in Figs. 1, 6, 7, and 8 a safety spring-stop I for the swinging frame E. This device is secured to an arm *f'* of the post F and arranged in a horizontal position. It consists of a curved arm *i*, having a spring-clasp *i²*, which receives and holds the rod *e* of the frame E when the latter swings around into position, as shown by the dotted lines in Fig. 1. The said arm *i* is attached to stretch or tension springs *i³*, which are arranged in the barrels *i⁴*, arranged parallel and secured to a plate *i⁵*, which is removable and reversible. The said plate *i⁵* rests upon and is supported by a fixed plate *i⁶*, secured on the arm *f'*. The means for attaching it so that it may be reversed consist of a shouldered catch *i⁷* and a pin or stud *i⁸*. (See Fig. 6.) The said

catch i^7 enters a slot, and the pin i^8 enters a hole in the plate i^9 . It is apparent that by this means the spring-stop I may be arranged to engage and arrest the swinging frame E in either direction, since it is adapted to be reversed by raising its free end, so as to release the pin i^8 , and then draw it diagonally upward, so as to release the catch i^7 .

Within the car C (see Fig. 2) I arrange another spring-stop J for receiving the bar d of the swinging frame D, attached to the car. There may be two such stops employed to receive both of the horizontal bars of frame D, if preferred. The stop comprises curved springs j , which are bent outward at their front ends to facilitate the entrance of the rod d and the spring-stop proper, j^2 , against which the rod d strikes.

It will be understood that mail-bags may be received and delivered simultaneously at any station. For this purpose the swinging frames D and E are swung outwardly from the car C and the post F, respectively, as shown in Figs. 1 and 2. The mail-bag to be delivered from the car is suspended from the frame D, while the mail-bag to be delivered to the car at the station is suspended from the swinging frame E. The means for suspending and automatically releasing the mail-bags is shown best in Figs. 11 and 12. It consists of curved spring fingers or jaws k , which are arranged opposite and journaled on the rods d and e and held normally closed by wire springs k^2 . The latter are coiled about the rods d and e , and the jaws open vertically. The device K is held in normal horizontal position by set-screws k^3 and k^4 . The screw k^3 passes through the shank or journal portion of the upper jaw k , and the screws k^4 pass through portions of the lower jaw k' . When the device K is pointed in one direction, as shown in Fig. 12, the screws k^4 hold it horizontal, and the upper jaw k is left free; but when the device K is reversed, so as to point in the opposite direction, the screws k^4 are loosened and the screw k^3 tightened, so as to leave free the other jaw k' , which is then uppermost. Thus whichever jaw is uppermost is the one required to be left free to be raised for the purpose of releasing a mail pouch or bag. Such upper jaw is raised automatically by means of a spring lever-arm L, which is coiled about the rod d or e and extended down to a pendent lever or tappet M. When such tappet is struck by swinging frame D or E, it swings forward and rotates the spring L on the adjacent rod, so that its free arm l engages the upper portion of the spring k^2 , as shown in Figs. 11 and 12, and thereby raises jaw k and releases the mail-bag. It will be understood that when the device K is reversed (as may be required when the frame E is located on the opposite side of the track) the other arm l engages the spring k^2 . The device K, which suspends a mail-pouch from the upper bar or rod d' of the swinging station-frame E, has such tappet-arm M alone; but

the device attached to the swinging car-frame D has a torsion-lever N attached to it, as shown best in Fig. 5. This lever extends beneath the rod d' , and its inner end is flattened horizontally and lies between the jaws of the spring-catch O, (see Fig. 4,) whose curved free ends embrace and clasp the rod d' . Such catch is attached to the casing or jamb of the car-door and serves to hold the frame D open or swung out, as shown in Figs. 1 and 2, against pressure of the wind and the swaying motion of the car.

It will be seen that when the pendent tappet M strikes the rod or bar e of the extended station-frame E the bar N will be turned so that its flat end will assume an angle and open the catch O, as shown by dotted lines, Fig. 4, thus releasing the rod d , so that the frame D swings into the car.

The general operation of my invention, briefly stated, is as follows: Upon approaching a mail-station the frame D is swung out of car C, with a mail-pouch suspended by a device K, attached to the upper rod d . A catcher A is also suspended from the same rod, as shown in Fig. 1. The frame E is also swung out at the station and a mail-pouch hung from device K on its rod e . Suppose the car to be moving in direction of the arrow, Fig. 2. Then the rod d of car-frame D will strike the tappet M on rod e' of station-frame E and cause instant release of the pouch there suspended, which pouch will fall into catcher A. On the other hand, the rod e of station-frame E will strike the tappet of the device K, which suspends a pouch from the rod d' of the car-frame D, and the catcher A receives such pouch. At the same time the torsion bar or lever N opens the catch O, so that the frame D may be swung into the car C. Thus reception and delivery of bags or pouches occur simultaneously and automatically as respects both car and station. In this operation the frames D and E swing free from their safety-catches O and H and back into engagement with safety-stops J and I, respectively.

The catchers A and B are preferably made of wire, as shown in Figs. 1, 2, and 9; but they may be made of other material—for example, sheet metal—as shown in Fig. 10. The said catchers are hollow cylinders, save that a quarter-segment is cut out, the horizontal side of the segment being closed and the vertical side open, as shown.

Having thus described my invention, what I claim as new, and desire to secure by Letters Patent, is—

1. In a mail-bag catching and delivering apparatus, a swinging frame journaled as specified and having a horizontal arm, a mail-bag catcher, and springs suspending it, whereby it is adapted to swing in a vertical plane, substantially as shown and described.

2. In a mail-bag catching and delivering apparatus, the combination with the horizontally-swinging frame having a horizontal arm, of the attachment comprising the mail-bag

catcher, a sleeve adapted to slide on said arm, and spiral springs connecting the catcher with said sleeve, as shown.

3. In a mail-bag catching and delivering apparatus, the catcher having a cylindrical body with a quarter-segment cut out, the horizontal side of said segment being covered and the vertical side open, substantially as shown and described.

4. In a mail-bag catching and delivering apparatus, the combination with a swinging frame attached to the car, of a spring-catch composed of curved jaws adapted to receive and clasp a portion of said frame the catch being secured to the car alongside the door, substantially as shown and described.

5. In a mail-bag catching and delivering apparatus, the combination with a swinging frame, of a spring-catch which is set vertically and recessed at its upper end, and adapted to swing in a vertical plane, and a spring which holds the same normally vertical, whereby said catch is adapted to engage and hold the frame normally extended and to lock and release the same when due pressure is applied, substantially as shown and described.

6. In a mail-bag catching and delivering apparatus, the combination with a swinging frame, of a spring safety-stop, and a catch for receiving and holding the frame closed or out of use, substantially as shown and described.

7. In a mail-bag catching and delivering apparatus, the combination with a swinging frame, of a spring stop and holder comprising tension-springs, and a curved arm attached to the same, and having a spring-clasp for receiving a portion of the frame, substantially as shown and described.

8. In a mail-bag catching and delivering apparatus, the combination with a swinging

frame, of a spring stop or buffer which is adapted for reversal, and to be held fixed in either position, substantially as shown and described.

9. In a mail-bag catching and delivering apparatus, the combination with a swinging frame, and a fixed plate having a slot as specified, of the spring stop or buffer having a plate provided with a catch adapted to enter and engage said slot, whereby the stop is adapted for reversal, as specified.

10. In a mail-bag catching and delivering apparatus, the combination with a swinging frame, of the device for suspending and automatically releasing a mail bag or pouch, the same comprising opposing jaws, clamp-screws for holding the same extended horizontally, the upper jaw being left free, and a spring for holding the jaws normally closed, a spring-lever for engaging and opening the upper jaw, a tappet connected with such spring-lever, and pendent therefrom and adapted to be operated in the manner described.

11. In a mail-bag catching and delivering apparatus, the combination with a swinging frame attached to a car, and a spring-catch which holds the said frame normally open, of a device for suspending a mail-bag, a torsion-lever suspended from said frame, and its inner end engaging said catch, substantially as shown and described, whereby when said torsion-lever is actuated by contact with a frame or device at a station, it is rotated more or less to open the jaws of the catch and thereby release a swinging frame held by the latter, as specified.
